UNITED STATES PATENT OFFICE.

ALFRED H. WILLETT, OF WEST NEW YORK, AND HARRY S. MARTIN, OF RIDGEWOOD, NEW JERSEY, ASSIGNEES TO AMERICAN ARCH COMPANY, OF NEW YORK, N. Y., A CORPORATION OF DELAWARE.

BAFFLE-WALL BRICK.

Application filed March 3, 1919. Serial No. 280,338.

To all whom it may concern:

Be it known that we, ALFRED H. WILLETT and HARRY S. MARTIN, citizens of the United States, respectively residing at West New

5 York, in the county of Hudson and State of New Jersey, and at Ridgewood, county of Bergen, and State of New Jersey, have invented certain new and useful Improvements in Baffle-Wall Brick, of which the

10 following is a specification.

This invention relates to baffle wall brick and particularly to brick suitable for use in cross walls found in certain types of locomotive fire boxes, and for use in marine and

15 stationary furnaces.

It is one of the primary objects of our invention to provide an improved brick constructed in such manner that the same style and size of brick may be used both for the 20 cross wall proper and for capping the same, thereby reducing the number of brick patterns required and simplifying the application of the brick.

We accomplish the foregoing by means of 25 a construction which we have illustrated in preferred form in the accompanying drawings, wherein—

Figure 1 is a longitudinal section through a portion of a locomotive fire box illustrating 30 the application of our improved brick thereto; Figure 2 is a cross section through a portion of the fire box illustrating a portion of the refractory arch and our improved brick in plan view; Figure 3 is a 35 perspective view illustrating our improved brick when used as a cap brick; and Figure 4 is an end elevation of a brick showing the manner in which it fits between the circulation tubes of the box when used as a cap brick.

In Figures 1 and 2, we have illustrated 40 our invention as applied to a locomotive having a shallow fire box, for the reason that, while our invention is suitable for use in other connections, it is particularly useful in connection with fire boxes of such shallow type. The fire box A is constructed in the usual manner and is provided with a plurality of circulating tubes 6 connecting the front and rear water legs. It will

be observed that the circulating tubes at the forward end approach very closely to the level of the grates diagrammatically indicated by the dotted line 7.

The cross wall in the instance shown, 55 comprises a lower or body portion composed of a course of brick supported on the cross bearer or carrier 8 extending transversely of the fire box adjacent the front water legs, and an upper portion composed of a course of cap brick. It will be seen from inspection of Figure 1 that the lower course consists of our improved bricks laid on one side, and the cap or upper course, of the bricks set on edge. The bricks of the 60 lower course are locked in position engaging the tubes, and the cap bricks which support the arch C composed of a plurality of suitable bricks of any preferred type, are also locked in position as will further appear.

The improved form of brick will be described with reference to the position it occupies when being used as a cap brick, attention being directed particularly to Figures 3 and 4.

From inspection of these figures, it will be seen that the sides 9 and 10 of the brick are flat, as is the bottom of the brick, indicated at 11. The top of the brick on one side or face thereof, is chamfered beyond the median plane of the brick as indicated at 12, and on the other side it is provided with a curved or rounded surface 13, which merges into the face, or side 9 of the brick. It will be seen, therefore, that the top of 85 the brick is somewhat of an inverted V-shape in form. The ends 14 and 15 of the brick each have a portion thereof cut away to provide a socket-like recess 16 adapted to fit the circulation tubes 6. The end portions 17 and 18 of the top portion of the brick are inclined as indicated in Figures 3 and 4, for the purpose of permitting such top portion to be inserted between tubes.

Referring now again to Figure 1, it will 95 be seen that the lower course of the cross wall is comprised of our improved brick laid on the cross bearer or carrier 8 with the side 10 faced downward. In this position the bricks will engage the circulation tube 6 in 100

such manner that forward movement of the course of bricks is prevented. By this means, in conjunction with the lip 19 of the cross bearer, it will be seen that the lower course of bricks is substantially locked in place, as against longitudinal displacement. The cap bricks rest on the bricks of the lower course with their socket portions 16 engaging the circulation tubes 6, such engagement preventing the cap bricks from shifting forwardly. The weight of the arch C prevents the cap brick from shifting rearwardly, the arrangement locking the cap brick in position. Vertical jostling of the lower course of brick is prevented by virtue of the fact that the cap brick sockets engage the circulation tubes and thereby prevent upward movement of the cap bricks, which in turn prevent any upward displacement of the lower course of bricks. The lower course of the arch bricks engage the rounded surfaces 13 of the cap bricks, an arrangement which permits the bricks to accommodate themselves to differences in the 25 inclination of the tubes.

It will be seen from the foregoing that we have provided a simple form of brick which may be utilized both for the courses of the cross wall and to cap the cross wall, the construction being such that all of the bricks are securely locked in position. It will be obvious that the bricks are simple in application and that the number of patterns, and therefore the cost, is reduced.

35 We claim:

1. In a boiler fire box having inclined circulation tubes and means therebelow for supporting a cross wall, the combination of bricks adapted to be used in one position in the construction of the body portion of said wall and in another position in the construction of the cap portion, each of said bricks having a recess at each end which leaves a shoulder adapted to engage the under portion of an adjacent tube when the brick is in cap forming position whereby forward displacement of the brick is prevented.
2. In a boiler fire box having inclined circulation tubes, an arch supported thereon and means below the tubes for supporting a cross wall; the combination of bricks adapted to be used in one position in the construction of the body portion of said wall and in another position in the construction of the cap portion, each of said bricks having a recess at each end which leaves a shoulder adapted to engage the under portion of an adjacent tube when the brick is in cap forming position and an arch engaging surface on the top, said shoulders and said arch engaging surfaces cooperating with the tubes to sustain the arch in inclined position on the tubes.
3. In a locomotive fire box having circulation tubes, an arch supported thereon and

means below the forward ends of said tubes for supporting a cross wall; the combination of a plurality of bricks for constructing said wall which are adapted to rest in one position in the body portion of the wall and in another position in the cap portion of the wall, each of said bricks being cut away at each end so that when in cap forming position it can be introduced between a pair of tubes with the cut away portions leaving shoulders adapted to engage the lower portions of adjacent tubes and said shoulders bearing such relation to the tubes as to prevent displacement of said bricks and thereby of the arch, the arch being adapted to bear against the said bricks in a direction to force them against the tubes.

4. In a boiler fire box having a plurality of inclined circulation tubes carrying an arch and means therebelow for supporting a cross wall; the combination of a plurality of bricks adapted to be used in the construction of said wall which can be placed in one position in the formation of the body portion of the wall and in another position in the formation of the cap portion, each of said bricks having cut away portions at the ends leaving shoulders which, in cap forming position, are adapted to engage the under faces of adjacent tubes and also formed with a face engaging the lower end of the arch, the relation between tubes, bricks and arch being such as to prevent displacement of the bricks and thereby of the arch.

5. In a locomotive fire box having circulation tubes, an arch supported thereon and means below the forward ends of said tubes for supporting a cross wall; the combination of a plurality of bricks for constructing said wall which are adapted to rest in one position in the body portion of the wall and in another position in the cap portion of the wall, each of said bricks having one tube engaging surface when resting in body forming position and a pair of tube engaging surfaces when resting in cap forming position, said pair of surfaces being formed by cutting away each end of the brick to leave shoulders adapted to engage the under portions of adjacent tubes, said shoulders bearing such relation to the tubes as to prevent displacement of the bricks and thereby of the arch, the tube engaging surface when the bricks are in body forming position acting as an arch engaging surface when the bricks are in cap forming position.

6. A baffle wall for a fire box having an inclined arch supported on inclined circulation tubes comprising in combination a plurality of counterpart bricks adapted to be used in one position in the construction of the body portion of the wall and in an-

other position in the construction of the cap portion thereof, each of said bricks being provided with a socket like recess at its ends leaving shoulders adapted when in cap form-

5 ing position to engage the lower portion of adjacent tubes, said tubes bearing such relation to the shoulders as to prevent forward

displacement of said brick whereby it is adapted to sustain the inclined arch.

In testimony whereof, we have hereunto ¹⁰ signed our names.

ALFRED H. WILLETT.

HARRY S. MARTIN.
